DESIGN FOR A DUAL WRENCH
OR THE LIKE

Fred E. Nettleton, Saginaw, Mich.

Application January 25, 1946, Serial No. 125,958

Term of patent 7 years

(Cl. D54—16)

To all whom it may concern:

Be it known that I, Fred E. Nettleton, a citizen of the United States, residing at Saginaw, in the county of Saginaw and State of Michigan, have invented a new, original, and ornamental Design for a Dual Wrench or the Like, of which the following is a specification, reference being had to the accompanying drawing, forming part thereof.

Figure 1 shows a top view of a dual wrench embodying my new design;

Figure 2 shows a side elevational view;

Figure 3 shows an end elevational view as seen from the left hand end of Figure 1;

Figure 4 shows a sectional end elevation taken between the handles and looking in the direction of the arrows 4—4 of Figure 1; and

Figure 5 shows an end elevational view as seen from the right hand end of Figure 1.

I claim:

The ornamental design for a dual wrench or the like, substantially as shown.

FRED E. NETTLETON.
